UNITED STATES PATENT OFFICE

118,319

DESIGN FOR A PILLOW

Allen Kandell, New York, N. Y.

Application March 14, 1939, Serial No. 83,573

Term of patent 3½ years

To all whom it may concern:

Be it known that I, Allen Kandell, a citizen of the United States, residing at New York, in the county of New York and State of New York, have invented a new, original, and ornamental Design for a Pillow, of which the following is a specification, reference being had to the accompanying drawing, forming part thereof.

I claim:

The ornamental design for a pillow, as shown.
